SORTING CASE

Sidney R. Bolling, Chicago, Ill.

Application April 7, 1948, Serial No. 19,560

3 Claims. (Cl. 312—241)

1

This invention relates to improvements in sorting case constructions.

In banking institutions where checks are employed as one of the means of doing business by customers, the banks are required to sort these checks according to banks, and also when returned from the clearing house they must sort them according to their customers' names, which entails quite a tremendous operation and cost in the conduct of a banking business. Sorting cases now used in banks are usually vertically disposed cases having a number of cells or compartments therein, into which the checks are placed during sorting operations. These individual cells, because no provision is made for holding the check in a vertical position so that it is readily removable and visible, offers no means for efficient and quick use, because of the necessity of groping on the floor of the cell to make sure that all of the checks deposited during the sorting operation are taken out when the sorting operation is finished. Broken fingernails, bruised fingers and great fatigue usually accompany this sorting operation, thereby causing a large turnover of employees. Furthermore, the sorting cases are set up in long banks or groups and occupy valuable space when not being used, because cases of this character are of single use design.

It was to overcome these and numerous other inherent defects that the present invention was devised.

The main objects of this invention are to provide a sorting case of new and improved design; to provide a sorting case which is adapted to be collapsed when not in use so that it may be used as a desk or table; to provide in a device of this character a shallow box-like frame having a series of cells or chambers having means incorporated therein and having means in the individual cells to cause articles being sorted to lie in a substantially vertical plane; to provide a device of this character wherein means are provided to readily and quickly remove the articles being sorted; to provide in a device of this character a series of cells so arranged as to prevent articles being sorted and placed therein from falling to the extreme rear of the individual cell; to provide a device of this character which will automatically cause the sorting case to be raised from inoperative to operative position upon movement of the cover or top thereof; to provide a device of the character described wherein movement of the cover or top will automatically and simultaneously move the sorting

case from inoperative to operative position and vice versa; and to provide a construction of the character described which is portable in nature, inexpensive to manufacture and extremely efficient in operation. Other objects will become apparent from the following specification.

An illustrative embodiment of this invention is shown in the accompanying drawings in which

Fig. 1 is a perspective view of my device 10 in open or operative position.

Fig. 2 is a fragmentary perspective view, partly in section, illustrating one of the cells or chambers of the present invention and taken substantially on the line 2—2 of Fig. 1.

Fig. 3 is a sectional view taken on the line 15 3—3 of Fig. 2.

Fig. 4 is a side view of the device of my invention showing the sorting case in closed position and illustrating the use of the device as a desk or table. The side wings of my invention, as shown in Fig. 1, are not illustrated for clarification purposes and the lower portion of the device is shown broken away.

Fig. 5 is a side elevational view partly in section showing the sorting case of my invention 25 in operative position, the lower portion of the legs being shown broken away.

Fig. 6 is an enlarged, detailed face view, partly in section and shown partly broken away, of the spring arm which facilitates shifting of the sorting case.

Fig. 7 is an enlarged sectional view of the mechanism shown in Fig. 6, but showing the spring arm as it would appear when the sorting case is in non-operative or closed position.

Fig. 8 is a sectional view taken on the line 30 8—8 of Fig. 6.

Referring in detail to the drawings, the embodiment shown is especially designed for use in banking institutions and particularly for use in sorting checks. The device comprises a sorting case generally indicated by the numeral 1, having side, bottom and rear walls, 2, 3, 4, 5 and 6 respectively, and a series of horizontally disposed dividing partition walls 7 and a series of vertically disposed dividing partition walls 8, whereby to form a series of individual cells, chambers or compartments in said case.

Each cell is provided with a diagonally disposed substantially vertical extending member 9, arranged across the lower right-hand corner of the cell and extending upwardly substantially halfway between adjacent partition walls 7 and extending lengthwise substantially two-thirds to three quarters across the area defined by the

walls 8 of each compartment, thereby being diagonally disposed in both horizontal and vertical planes. A second vertically disposed member 10 is positioned rearwardly of the member 9 and covers the upper right-hand corner of the compartment above and behind the member 9 (see Fig. 2). The lower portion or edge of the member 10 is secured to the rear edge of a diagonally extending member 11. The front portion or edge of the member 11 is secured to the upper portion of the member 9. The member 11 is secured to the members 9 and 10 in any suitable manner such as by nails 11'. (See Fig. 3.)

It is to be noted that the member 9 lies in a diagonal plane, so that when a check is snapped or thrown in a cell in the usual and customary manner, it will tend to stand on its lower long edge and lie against the member 9 whereby it will stand in a substantially vertical plane.

The vertically extending partition walls 8 are provided with a series of notches or cut-outs 12 whereby ready access to the interior of the cell can be had from the side as well as from the front.

The sorting case 1 is pivotally secured to the front upper cross bar 13 of the supporting structure by any suitable means such as hinges 14. The supporting structure comprises a pair of front and a pair of rear legs 15 and 16 respectively and supporting braces 17 to lend rigidity to the supporting structure. The upper portion of the supporting structure comprises in addition to the upper front cross bar 13, a rear cross bar 18, side bars 19 and cross bar 20.

The lower supporting structure is also provided with a back upright rear closure member 21, suitably anchored in position and held rigidly in the construction by an angle bracket 22, the vertically extending leg of the bracket 22 being secured to the member 21 while the horizontally disposed lower leg of the angle bracket 22 is securely fastened to the side braces 19. The method of fastening may be by means of wood screws 23 or the like.

The cover, or table, or desk top 25 is pivotally secured to the upper end of the member 21 by any suitable means such as by hinges 26, and is of a size to more than completely cover the open face of the sorting case when the same is inoperative or closed position. The forward end of the top 25 is secured to the sorting case 1 by a pair of link arms 27 and 28. I provide a duplicate pair on each side of the sorting case 1 for ease of operation, but only one pair is shown in the drawings. The upper end of the link arm 27 is pivotally secured to a bracket 29 located on the underside of the top 25 adjacent the side edge, by any suitable means such as by a bolt or rivet 29'. The lower end of the link arm 28, as viewed in Fig. 5, is pivotally secured to the sorting case 1 in any suitable manner such as by a rivet or screw 30. The two link arms are pivotally secured together in any suitable manner such as by a bolt or rivet 31.

The mechanism for assisting in raising the sorting case in the position shown in Fig. 5 from the position shown in Fig. 4, is a spring construction member comprising a hollow tubular arm 32 having a roller 33 rotatably secured to the upper end thereof as viewed in Fig. 5. The lower end of the tubular member 32 is rigidly bolted to the upper leg 34 of an offset bracket 35 by means of a pair of bolts 36. A cradle 37 is secured to the offset bracket 35 by means of a pin

38 which is secured to the cradle 37 by threaded engagement as shown at 39 in Fig. 8. The upper end of the pin 39 extends through an aperture 40 in the horizontally extending portion 41 of the bracket 35. A helical compression spring 42 is positioned around the pin 38. The upper end of the spring 42 bears against the lower face of the portion 41 of the bracket 35 while the lower end bears against the upper portion of the cradle 37 (see Fig. 8). The cradle 37 is provided with cammed surfaces 43, 44 and 45.

A fulcrum arm 46 is rigidly secured to a bearing plate 47 by any suitable means such as by welding. The lower end of the leg 34' is pivotally secured to the arm 46 by means of a bolt 48.

When the sorting case 1 is in inoperative position, the cradle 37 is rocked about the fulcrum cam face 49 so as to force the cradle to the left as viewed in Fig. 7, thereby compressing the spring 42 so that when the sorting case is moved to the position shown in Fig. 5, the action of the spring will cause the arm 32 to be forcibly moved to the left about the cam face 49, thereby causing the sorting tray to be moved about the pivot hinge 14 until the camming surface 45 abuts against the stop 50 (see Fig. 6).

The bearing plate 47 is secured to the front vertical support member 15 and cross bar 19 in any suitable manner such as bolts 51. It is to be understood that I employ two spring constructions for raising the sorting case, each fastened adjacent the vertical front supporting legs 15. The foregoing spring construction is old in the art and conventional in design and therefore is not claimed as a part of the present invention.

The forward movement of the sorting case 1 about its pivot 14, is limited by a chain, or the like, 52, one end of which is secured to a screw eye 53 anchored medially of the ends of the cross bar 20 and thereto, while the other end of the chain 52 is secured to a screw eye 54 anchored in the bottom wall 6 of the sorting case adjacent the wall 2 and medially of the side walls 3-4.

In order to prevent accidental closing of the sorting case 1 I have provided a rubber pad 55 on the inner face of the top 25 against which the wall 2 will bear, and it will be apparent also that the angular position of the sorting case may be set from the position shown in Fig. 5 to approximately 45° due to the friction holding action of the rubber pad 55 against the wall 2 of the sorting case.

Side frames or guards 56 and 57, having rubber beads 58 and 59 respectively around the exposed edges thereof, are secured to the sides of the top 25 in any suitable manner and depend therefrom. The purpose of the side frames is to prevent injury to persons standing around the sorting case when the same is lowered to the position shown in Fig. 4, because the side frames or guards 56 and 57 will tend to force a person to withdraw his arms if they should inadvertently be inserted into the interior of the device behind the sorting tray.

In order to insure relatively quiet closing of the device, I have provided a pair of plunger elements generally indicated by the numeral 60, only one being shown in the drawing, the second one located diametrically opposite the one shown in the drawing and each is positioned on the upper edge of the side frame members 19.

The plungers 60 are of the usual common type found on the open market. The plungers are only for the purpose of preventing the sorting case from banging against the cross bar 20 when the

case 1 is being lowered to the position shown in Fig. 4.

It will now be apparent from the foregoing that when the device of my invention is not being used as a sorting tray, it may be used as a table or desk. This is an important feature since in present practice in banking institutions both a sorting case and a table on which the employees may complete the sorting operation are required.

Although but one specific embodiment of this invention is herein shown and described, it will be understood that numerous details of the construction shown may be altered or omitted without departing from the spirit of the invention as defined by the following claims.

I claim:

1. A device of the class described comprising a supporting frame, a sorting case pivotally mounted to said frame, a table top pivotally secured to said frame, link means secured to said case and top whereby movement of said top will automatically cause a corresponding movement of said case, a plurality of cells in said case, and a stepped member positioned in each of said cells with one edge thereof adjacent the front edge of one of the walls of said cell and extending diagonally rearwardly substantially to the rearmost opposite corner of said cell.

2. A device of the class described comprising a supporting frame, a sorting case pivotally mounted at its lower front end to the upper front end of said frame, a table top pivotally secured to the upper rear end of said frame and of a surface area greater than the surface area of said case, link means secured to said top and case whereby movement of said top about its pivot will automatically cause a corresponding movement of said case, a plurality of cells in said case, a stepped member in each of said cells positioned diagonally therein, a cut-away portion in the side walls of each of said cells, spring means positioned on the upper side of said frame adjacent the rear end thereof and arranged to bear against the bottom wall of said case and force said case

upwardly and forwardly about its pivot upon movement of said top in an upwardly and rearwardly direction in cooperation with said link means, resilient friction means positioned on the lower face of said table top adjacent the front edge thereof and extending rearwardly substantially medially on the lower face of said top to angularly position said case in open position, and means to limit the forward movement of said case.

3. A device of the class described comprising a supporting frame, a sorting case pivotally mounted at its lower front end to the upper front end of said frame, a table top pivotally secured to the upper rear end of said frame, link means secured to said case and top whereby upward and rearward movement of said top will automatically cause a corresponding movement of said case, in an upward and forward direction, a plurality of cells in said case, and means in each of said cells for positioning articles placed therein on one of their edges, said means comprising a stepped member positioned in each of said cells with one edge thereof adjacent the front edge of one of the walls of said member and extending diagonally rearwardly substantially to the rearmost opposite corner of said cell.
